UNITED STATES PATENT OFFICE.

FLOYD J. METZGER, OF NEW YORK, N. Y., ASSIGNOR TO AIR REDUCTION COMPANY, INC., A CORPORATION OF NEW YORK.

ACETYLENE TANK.

1,419,746.

Specification of Letters Patent. Patented June 13, 1922.

Application filed November 19, 1920. Serial No. 425,089.

To all whom it may concern:

Be it known that I, FLOYD J. METZGER, a citizen of the United States, residing at New York, in the county of New York, State of New York, have invented certain new and useful Improvements in Acetylene Tanks; and I do hereby declare the following to be a full, clear, and exact description of the invention, such as will enable others skilled in the art to which it appertains to make and use the same.

This invention relates to storage receptacles for acetylene, and comprises a closed tank filled with porous material capable of absorbing a solvent for the acetylene, which holds the acetylene in solution until it is required for use, and prevents the spread of any local decomposition of the acetylene to the remainder of the gas. Such receptacles have been in use for a number of years, and various kinds of porous material have been suggested or used, including charcoal and corn-pith. Probably the most successful material heretofore known has been corn-pith, which, because of its resilient and highly porous character, and the relatively small size of the pores, has been successfully used as an absorbent for acetone, acetaldehyde, methylacetate or mixtures thereof, in which the acetylene is dissolved.

As a result of extended research to obtain a material superior to corn-pith, which is difficultly obtainable, relatively expensive and always contaminated with more or less waste material from the corn stalk, it has been discovered that the wood of the balsa or ochroma lagopus may not only be substituted for corn-pith, but, in fact, presents numerous advantages over corn-pith, and is adapted therefore, to displace the latter material as a filler for acetylene storage tanks.

Balsa is a tropical wood, which, either in its natural state or in extensively cultivated areas, is being produced in quantities, and is available for the purpose to which the present invention is directed. The wood of the balsa is similar in appearance to basswood, but is lighter than cork, weighing when dry, only 7.3 pounds per cubic foot. It is made up of barrel shaped, thin walled cells of practically pure cellulose, and is extremely porous, because of its cellular texture and substantial absence of fibers from its structure.

When the wood is chipped, or otherwise reduced to a relatively finely divided state, it has a porosity exceeding 90 percent, thus permitting the maximum filling with the solvent acetone, while at the same time insuring the presence of the acetone in a relatively finely divided and separated condition, so that the acetylene dissolved therein is incapable of propagating decomposition disturbances in the mass. Another peculiarity of this material is its great elasticity which insures the filling of all of the space within the tank, and when the acetone is added, the material swells materially, thus preventing any possibility of spaces in which acetylene would be present in a free condition.

The filling may consist entirely of the finely divided balsa, as hereinbefore described, which may be packed directly in the tanks, or it may be molded into blocks of such size and shape as to completely fill the tank. Preferably the finely divided balsa is mixed with a quantity of inert and porous material such as infusorial earth or charcoal. Asbestos may also be used for this purpose. It may be desirable, moreover, to include in the mixture a cement such as sodium silicate, colloidal silicic acid, glue, albumin, etc.

The accompanying drawing illustrates an acetylene tank in longitudinal section with the filling in place.

In preparing the tank, which is preferably a drawn steel shell 5, the outlet spud 6 and valve 7 are secured in place, and the balsa or composition including balsa is introduced to the tank, and is compressed therein by the use of suitable means capable of applying the desired pressure to the mass. When the tank has been completely filled, and the material is sufficiently compressed, the bottom 9, having one or more fusible plugs 8, is secured in place preferably by welding. A suitable quantity of acetone or other suitable solvent is then introduced under pressure preferably in several portions, in order that the acetone may entirely saturate the porous material. When the filling with acetone is complete, the tank may be charged with acetylene from the compressor line.

The results of tests demonstrate that balsa is an ideal material for filling acetylene tanks, and that the material has a maximum

capacity for absorbing acetone, and consequently for the storage of acetylene. In addition, the filling material is extremely light, and the weight of the acetylene tank is thus materially reduced. Owing to the 5 resilient character of the balsa, and its capacity for swelling when the tank is filled with the solvent, it is absolutely impossible for any pocket or void to be formed within 10 the tank, either by settling or otherwise, in which free acetylene might accumulate. Balsa is available in large quantities, and is relatively inexpensive. It may be readily reduced to a finely divided state by the use 15 of chipping machines or other devices well known and commonly used in the manufacture of wood pulp and for similar purposes.

Various changes may obviously be made in the arrangement of the tank and in the 20 proportions of the mixture employed as a filler therein; the basic feature of the present invention being the use of balsa as a filler for acetylene tanks.

I claim:

1. A tank adapted for the storage of 25 acetylene gas, said tank containing balsa wood in a relatively finely divided condition, and a solvent for acetylene gas.

2. A tank adapted for the storage of 30 acetylene gas, and having an absorbent filling, consisting substantially of a compressed, resilient body of balsa wood in a relatively finely divided condition, and a solvent for acetylene gas.

3. A tank adapted for the storage of 35 acetylene gas said tank containing wood of the ochroma family, the wood being in a relatively finely divided condition, and a solvent for acetylene gas.

4. A tank adapted for the storage of 40 acetylene gas and containing chips of a light porous wood and a solvent for acetylene gas.

In testimony whereof I affix my signature.

FLOYD J. METZGER.
